UNITED STATES PATENT OFFICE.

ALBERT MANVERS AND HENRY PHILLIPS, OF SYDNEY, NEW SOUTH WALES, AUSTRALIA.

APPARATUS FOR CREATING AND MAINTAINING A VACUUM.

No. 863,863.

Specification of Letters Patent.

Patented Aug. 20, 1907.

Application filed May 9, 1906. Serial No. 316,036.

To all whom it may concern:

Be it known that I, ALBERT MANVERS, a subject of the King of Great Britain and Ireland, and a resident of 51 Regent street, Sydney, in the State of New South Wales, Commonwealth of Australia, and HENRY PHILLIPS, a subject of the King of Great Britain and Ireland, and a resident of 51 Regent street, Sydney, in the State of New South Wales, Commonwealth of Australia, have invented new and useful Improvements in Improved 10 Apparatus for Creating and Maintaining a Vacuum of which the following is a specification.

This invention relates to a small appliance to be connected to the chamber to be exhausted, and consists of an outer casing which is to be connected to the chamber to be exhausted and an inner tube, made in sections, to be connected to any suitable supply of water under a pressure of from 35 to 40 lb. to the inch. The first section of the inner tube terminates in a perforated disk, within a collar, that is perforated with holes to allow of 15 communication between the space around the inner tube and the inside of the tube. The whole appliance terminates in a bulb, or chamber, into which the water pours from the inner tube, and the water in this chamber serves as a seal to prevent back pressure of air.

20 In the accompanying drawings:—Figure 1 is a longitudinal vertical section of the whole apparatus. Fig. 2 is a vertical cross section of the same taken on the line 1—2 of Fig. 1.

(A) is the outer casing and is provided with a nipple (B) whereby it may be connected to the chamber to be exhausted. Screwed axially within the casing (A) is an inner compound tube (C) adapted to be connected, at one end, to any suitable supply of water under a head, or pressure, of not less than 35 lb. to the inch. 25 The inner tube (C) is of considerably less diameter than the inside of the casing (A) so that there shall be a vacant annular space (A¹) between the outside of the inner tube (C) and the inside of the casing (A). The inner tube (C) is made in four or more sections, any two 30 adjacent sections being connected together by tapped collars (D): These collars (D) are perforated with holes (d) whereby there may be a communication between the annular space (A¹) and the inside of the compound tube (C). The first section of the inner tube (C), 35 (or that nearest to the source of water supply), terminates in a perforated disk. The aggregate area of the perforations (c) in the disk should not be greater than half the sectional area of the bore of the tube (C). The perforations (c) will have the effect of splitting up the 40 comparatively large column of water, that enters the tube (C), into a number of smaller columns, thereby presenting a relatively greater surface. The passage of the water through the first collar (D) will induce a current of air from the annular space (A¹), and, incidentally, from the chamber to be exhausted. This air

will be induced through the perforations (d), in the collar (D), and will mix with the divided streams of water that are passing along the tube (C) through the collar (D), and will thus aerate the water. The aeration of the water will be repeated at the subsequent collars (D) as the stream of water passes along the compound tube (C).

The extreme end of the compound tube (C) enters a relatively large bulbous chamber (E), into which it discharges the aerated water. This aerated water, being of greater bulk than when it entered the tube (C), will soon fill the chamber (E) and thereby form an elastic water seal and prevent any back pressure of air along the exhaust pipe (F).

It is important that the outer casing (A) should be 70 proof against leaks of air from without. To this end a rubber washer (G), secured by a nut (g), is placed over the end where the water enters the tube (C). At the opposite end of the tube (C) the same result is obtained by the rubber washer (H), and the metal washer (h). 75 These two washers (H h), are secured and maintained against a shoulder within the casing (A) by means of a hollow nut (J) that is screwed into the end of the casing (A). The metal washer (h) will also serve to center and maintain the free end of the compound tube (C) 80 in a position parallel to the longitudinal axis of the whole appliance. It is important to remark that the bulbous chamber (E) is screwed on to the outside of the casing (A) and is provided with a flexible washer (e) to prevent leakage.

The ends of the sections of the tube (C), that face the incoming water are made bell-mouthed as at (c¹), while the opposite ends of the sections are square or flat as at (c²). This is to prevent the impingement of water against a flat surface and to reduce friction.

In the event of an accident occurring, and water flooding the annular space (A¹), a small ball valve (K) is placed beneath the nipple (B) so that any flood of water from the annular space (A¹) should lift the cork ball and close the entrance to the passage through the 95 nipple. Furthermore, should the case (A) be flooded with water, the water may readily be removed by opening the valve (M). This valve (M) is preferably a flute key valve closing a small passage (m). It is but necessary to depress the lever and open the valve and the 100 vacuum in the casing (A) will be immediately destroyed and the water will flow out.

Having now described our invention, what we claim as new and desire to secure by Letters Patent is:—

1. An apparatus for creating a vacuum comprising an 105 outer casing, an inner casing tube in sections, perforated collars connecting the tube together and a perforated flat disk at the end of the tube nearest the receptacle to be exhausted.
2. In apparatus for creating a vacuum, an outer cas- 110 ing hermetically sealed against the outer air, means for

connecting such casing with the vessel to be exhausted, a tube, in sections axially placed within the outer casing, means for connecting the first section of the tube with a suitable supply of water under pressure, a perforated disk terminating the first section of the tube, collars to connect the adjacent sections of tube together, such collars having perforations whereby communication is established between the inside of the casing and the inside of the tube, a bulbous cover entirely covering the discharge end of the apparatus said cover being screwed over the

end of the outer casing and a discharge pipe leading from said cover, all as and for the purposes specified.

Dated at Sidney, in the State of New South Wales, Commonwealth of Australia, this 7th day of April, A. D. 1906.

ALBERT MANVERS.
HENRY PHILLIPS.

In the presence of—
MANFIELD NEWTON,
ALBERT MASSEY.
